UNITED STATES PATENT OFFICE.

JOSEPH-WILFRID DUMONT, OF KATAHDIN IRON WORKS, MAINE.

FUNNEL.

Application filed December 23, 1922. Serial No. 608,671.

To all whom it may concern:

Be it known that I, JOSEPH-WILFRID DUMONT, a subject of the King of Great Britain, residing at Katahdin Iron Works, in the county of Piscataquis and State of Maine, have invented new and useful Improvements in Funnels, of which the following is a specification.

This invention relates to funnels for use in filling receptacles of any kind with any liquid, and has for its object the provision of a novel funnel which is equipped with means for closing the outlet end thereof when the receptacle is full and also for closing this end while the funnel containing the liquid is being transported from the filling station to the receptacle to be filled, as occurs in many instances.

An important object is the provision of a funnel of this character in which the member for closing the outlet end is formed with air passages communicating with an air tube which will permit the air within the receptacle to escape as the liquid is poured in, this feature being of great advantage in saving time during the filling operation.

An additional object is the provision of a funnel of this character which will be simple and inexpensive in manufacture, highly efficient in use, durable in service and a general improvement in the art.

With the above and other objects and advantages in view the invention consists in the details of construction to be herein-after more fully described and claimed and illustrated in the accompanying drawings, in which:

Figure 1 is a longitudinal section through the funnel showing it inserted into a receptacle being filled,

Figure 2 is a plan view,

Figure 3 is a horizontal section taken at the neck of the funnel,

Figure 4 is a horizontal section taken through the stopper member or valve,

The remaining figures are detail views.

Referring more particularly to the drawings the letter A designates any receptacle to be filled with a liquid, and B represents the neck thereof. In carrying out my invention I provide a funnel shaped body 10 of conventional design having the usual main portion 11 and reduced or neck portion 12 which is insertable within the receptacle to be filled. At one side this funnel member carries a handle 13. The material and size

of the funnel is a matter of no great consequence as any desired variations in these details may be resorted to.

Extending transversely of the funnel are spiders 14 and 15 suitably mounted in place and constituting bearings for a vertically extending air tube 16 which has its upper end coiled or curled to provide a handle 17. This air tube is slideable through the spiders and has its lower end carrying a stopper or valve 18 having a conical upper end 19 designed to enter and close the outlet end of the funnel. The tube 16 extends partly through this valve or stopper and has its lower end split to define a plurality of tongues 20 which are forced in divergent relation through the material of the stopper and which have their free ends directed toward one another and forced into penetrating engagement within the stopper as shown at 21 for the purpose of rigidly securing the stopper to the tube. The stopper is also formed with a plurality of upwardly converging passages 22 which communicate with the lower end of the air tube, and the stopper is also formed with a central passage 23 communicating with the junctures of these inclined passages.

In the use of the device it will be seen that by pulling up upon the handle 17, the stopper 18 will be forced into the outlet end of the funnel so as to form a seal or closure therefor so that the funnel full of liquid may be carried from one place to another where the filling is to be accomplished. Assuming that the funnel is full and the stopper is closed, the operator inserts the outlet end of the funnel into the receptacle to be filled and releases his grip upon the handle 17. When this is done the weight of the contents will unseat the stopper 18 and permit the liquid to flow into the receptacle. If the device is not used in this way it may be used in the same manner as an ordinary funnel, that is it is inserted into the receptacle without it being necessary to manipulate the handle 17 or stopper at all. Liquid may then be poured into and through the funnel in the ordinary manner and as the liquid enters the receptacle it is apparent that the air displaced will pass out through the passages 22 and 23 into the tube 16 from which it will escape into the atmosphere. This feature is of great importance as permitting rapid filling of the receptacle. When the

receptacle becomes full the liquid will float the stopper and cause it to close the outlet end of the funnel so that no more liquid will enter the receptacle and cause overflowing thereof. When this occurs it is evidenced by the upward movement of the tube 16 and the operator may then hold the handle to keep the stopper closed and remove the funnel from the receptacle.

10 From the foregoing description and a study of the drawings it will be apparent that I have thus provided a simply constructed and consequently inexpensive funnel which will be highly advantageous in 15 point of economy together with its time and labor saving qualities. Owing to the simplicity of the construction and the fewness of the parts it is apparent that there is practically nothing to get out of order 20 so that the device should have a long life and satisfactorily perform all of its functions.

While I have shown and described the preferred embodiment of the invention it is 25 of course to be understood that I reserve the right to make such changes in the form, construction and arrangement of parts as will not depart from the spirit of the invention or the scope of the subjoined claims.

30 Having thus described my invention I claim:

1. A funnel comprising a tapered body terminating in a reduced spout adapted for insertion within a filling opening in a receptacle to be filled, guides within the body, a tube slidable through said guides and having one end formed into a handle loop projecting above the top of the shell, both ends

of the tube being open, and a buoyant stopper secured upon the lower end of the tube 40 beneath said spout and adapted to be moved upwardly for closing the same when the level of liquid within the receptacle being filled reaches a certain point, said stopper being formed near its upper end with passages leading from the outside thereof to the tube, said tube being formed with holes registering with said passages.

2. A funnel comprising a funnel shaped hollow body, supporting spiders therein, an axially extending tube having one end extending above the funnel and provided with a handle, and a buoyant stopper carried by the lower end of said tube and adapted to close the outlet end of the funnel, said stopper being provided with passages communicating with said tube for permitting the escape of air, and said tube extending to the bottom of the stopper and having both ends open.

3. A funnel comprising a funnel shaped hollow body, supporting spiders therein, an axially extending tube having one end extending above the funnel and formed into a handle, and a buoyant stopper carried by the lower end of said tube and adapted to close the outlet end of the funnel, the lower end of said tube extending through the stopper and being split to define a series of divergent arms embracing the bottom and sides of the stopper, the free ends of said arms having penetrating engagement with the stopper.

In testimony whereof I affix my signature.

JOSEPH-WILFRID DUMONT.
